UNITED STATES PATENT OFFICE.

FRANK L. WRIGHT, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,988, dated December 7, 1897.

Application filed October 23, 1897. Serial No. 656,231. Term of patent 14 years.

To all whom it may concern:

Be it known that I, FRANK L. WRIGHT, a citizen of the United States, residing at Chicago, in the county of Cook and State of Illinois, have invented a certain new and original 5 Design for Prism-Lights, of which the following is a description.

My invention relates to a design for prism-lights.

10 Figure 1 is a plan view of a light embodying my design. Fig. 2 is a section therethrough.

15 A is the body of the prism-light; B B, a series of prisms on one side thereof; C C, a series of dots, lines, or portions of lines on the other side. These dots and portions of lines

are arranged and related so as to produce a design on the prism-light, formed as it were, of broken, fragmentary, or interrupted lines.

The essential features of my design are 20 found in a prism-light having a substantially flat body with a series of prisms on one side and on the other a series of broken, interrupted, or fragmentary lines or forms arranged so as to produce a unitary pattern. 25

I claim—

A design for a prism-light, substantially as shown and described.

FRANK L. WRIGHT.
